UNITED STATES PATENT OFFICE.

JOHN M. CHRISTINE, OF FORD CITY, PENNSYLVANIA.

MEANS FOR CUTTING KERFS IN MINING.

1,404,835.

Specification of Letters Patent. Patented Jan. 31, 1922.

Application filed January 14, 1920. Serial No. 351,314.

To all whom it may concern:

Be it known that I, JOHN M. CHRISTINE, a citizen of the United States, and a resident of Ford City, in the county of Armstrong and State of Pennsylvania, have invented certain new and useful Improvements in Means for Cutting Kerfs in Mining, of which the following is a specification.

My present invention relates generally to the mining of minerals, and more particularly to novel means of cutting kerfs, the means especially having to do with the chain cutters of mining machines.

In so far as the means proposed by my invention are concerned, chains equipped with my improvement may be adapted to practically any type of mining machine now in use.

The primary object of my present invention is the provision of novel means whereby kerfs may be cut for the well known purpose with more efficient results along the various lines I will hereinafter specifically mention than can at present be done.

With this general statement in mind, the further objects and the resulting advantages of my invention can be more readily understood from the following description of the invention in detail, reference being made to the accompanying drawings, which form a part of this specification, and in which:

Figure 1 is a top plan view of a portion of a mining machine, illustrating in particular its cutter bar and chain.

Figure 2 is a side view of a portion of the chain equipped with my improvements.

Figures 3 to 6 inclusive are sectional views, more or less diagrammatic, illustrating the various steps in the novel method of cutting kerfs as proposed by my invention.

Figures 7 and 8 are partial sections respectively illustrating the operative and inoperative positions of the cleaning cutters at relatively opposite sides of the cutter bar.

Figure 9 is a side view of one of the chain links illustrating a proposed bearing adjustment.

Figures 10 and 11 are end views showing modified forms of mounting of the cleaning cutters.

Figure 12 is a sectional view illustrating a guard for the cleaning cutters.

Figure 13 is a perspective view of one of the digging cutters,

Figure 14 is a face view of one of the slot widening disks, and

Figure 15 is a perspective view of a modified form of widening disk.

Referring now to these figures, and particularly to Figures 3 to 6 inclusive, my invention proposes the cutting of kerfs in coal beds by first digging a slot 20 in the coal bed 21, by means of a digging cutter, and then gradually widening the slot thus formed by means of cutters successively moved into engagement with the face of the coal at spaced points above and below the dug slot until the full width of the kerf 22 is reached. Thus in Figure 3, the initial slot 20 is shown formed by a cutter 23 of the type illustrated in detail in Figure 13. This cutter is of a multiple construction, with a central opening 24 and with transverse cutting edges 25 at its several points, the cutter being rotatably mounted so as to rotate in its movement 75 against the face of the coal in order to break out the slot during the successive movement of its several cutting edges against the coal.

In Figure 4 a pair of cutting disks 26 are shown working against the face of the coal at spaced points above and below the original limits of the slot 20 in order to break out portions of the coal above and below the original slot and widen the slot to this extent. The cutters 26, one of which is seen in Figure 85 14, have central openings 27 and circular beveled edges 28.

In Figure 5 cutters 29 of similar types to the cutters 26 are shown with greater spacing between them, and by a comparison of this figure with Figure 6 in which disk cutters 30 appear, it will be noted that each pair of cutters have their cutting edges spaced apart increasing distances until the full desired width or height of the kerf 22 is reached. 95

In this way it is obvious the desired results are accomplished by means which are rotated by virtue of their engagement with the coal during their movement across the face thereof in contact therewith, and by virtue thereof of the power required to move the cutters and to effect the desired operation is greatly reduced. 100

By reference to Figure 1, wherein I have generally indicated a mining machine at 31, with its cutter bar 32, I have shown the digging cutters 23 and the cleaning cutters 26, 29 and 30 rotatably mounted on shafts

33 in connection with the links 34 and 35 of the chain which as usual extends in endless relation around the cutter bar and is driven counter clockwise, from the machine 31.

The links 34 and 35 are alternately closed and open, the open links 35 having side plates, between which the digging cutters 23 are disposed where these cutters occur, 10 and outwardly beyond which the cleaning cutters 29 are preferably mounted where these cutters occur. The first pair of cleaning cutters 26 are preferably carried by the closed links 34 and the finishing cutters 30 15 are also preferably carried by the closed links, the upstanding bearing portions 36 of which as seen in Figure 10, may either have angular bearings for the shaft of the finishing cutters 30 or, as seen in Figure 11, 20 the bearing portion 36^a may have angular shafts 37 on which these cutters 30 are mounted.

It is preferably, however, that the finishing cutters 30 be provided with sockets 25 movably engaging ball-shaped enlargements 38 carried by the bearing portions of the chain links as seen in Figures 7, 8 and 12, so that they can work to the angular position shown in Figure 7 in their engagement 30 with the coal at one side of the cutter bar and, upon assuming a parallel position as shown in Figure 8 at the opposite side of the cutter bar danger of dragging against either the top or base of the kerf is entirely avoided.

In hard coal, shale, or slate, the several cutting disks may, if desired, be formed as shown in Figure 15, their disk-like form remaining except that they are divided into 40 an annular series of radial teeth so that their movement into hard material is facilitated and power necessary for such movement is reduced.

The relative arrangement of the several 45 digging and cleaning cutters, including the finishing cutters, in connection with the chain, may be varied practically at will, dependent upon the existing circumstances of use including the degree of hardness of the 50 coal and the presence or absence of harder substances such as shale, slate, and the like. Adjustment may also be provided for in connection with the bearing portions 36 of the several links by utilizing rotatably 55 shiftable eccentric bearing members 42, with clamping blocks 43 slideable in cut out portions 44 and controlled by set screws 45. A guard rail 46 such as shown in Figures 1, 7, 8 and 12 is also utilized around the cutter bar 60 in connection with the cutters to prevent inward tilting of the outer portions of the cutting disks 30 toward one another at the rear or inactive side of the cutter bar and to thus maintain these disks 30 in horizontal position as in Figure 8 so that as

these disks round the outer end of the cutter bar they are naturally tilted outwardly and away from one another upon engagement with the coal as in Figure 7. It is of course to be understood that a guard rail 70 will be utilized for the purpose set forth upon both the upper and lower surfaces of the cutter bar.

It is thus obvious that in addition to the saving in power required to operate the 75 cutting chain, my invention, substituting as is does rotating cutters for the usual coal grinding and powdering bits, reduces the present frequent abrasion of bits and breakage to such an extent as to practically eliminate a great amount of time now lost in frequent changing of bits. Dust and fine coal is reduced to a minimum as through my improved method and means the coal is broken out, taking advantage of the natural 80 existing lines of fracture of the coal bed, in order to produce usable coal from the kerf. The machine proposed by my invention takes its power in a uniform manner without the sharp "peaks" in load when obstructions are 85 encountered, and according to my improved method and means, the machine has no tendency to either climb or drop nor leave "cores" in the kerf when cutting past shale, slate and the like. My invention avoids the heating 90 of cutters due to abrasion, permits of a faster rate of cutting to be maintained with less power, less expense of upkeep, and without excessive power in connection with either hard coals, shale, slate, and the like. 95 My invention also practically eliminates sharpening of the cutters, as well as the danger of gas ignition from overheated bits or sparks, leaves a smooth bottom for shoveling, is adapted to a rolling bottom, is instantly reversible, and is capable of more effective and efficient use in general than those devices now employed, and with less cost, less danger and greater value to the operator.

It is to be understood that the method 100 thus outlined may be employed in connection with rotary cutting disks or wheels as well as reciprocating bars, with nearly if not equal facility to its use with chain cutters as illustrated. It is also to be understood that any or all of the cutting disks 105 of the chain, as illustrated, may be provided with roller or ball bearings if it is so desired.

I claim:—

1. The herein described means for cutting kerfs in mining, which consists of a mining machine cutter chain having a plurality of links, a plurality of rotary cutters mounted thereon with their axes in planes substantially at right angles to the chain, certain of which cutters are of disk-like form with peripheral cutting edges and are vertically spaced in pairs the spacing between the disks of said pairs being varied throughout 110

- the length of the chain, and the disks of each pair being equi-distantly spaced above and below the longitudinal center of the chain, and certain of which cutters are 5 multi-pointed with transversely disposed cutting edges at their points and are disposed along the longitudinal center of the chain, the cutting points of the last mentioned cutters extending beyond the peripheral edges of the first mentioned cutters in 10 order to come into action against the face of the kerf previous to the contact of the first mentioned cutters with the face of the kerf.
- 15 2. A cutter chain for mining machines including a plurality of links, and a plurality of rotary cutters mounted in connection with said links, certain of which cutters form slot diggers disposed along the longitudinal center 20 of the chain and are multi-pointed and provided with transverse cutting edges at their points, and certain of which cutters are vertically alined in pairs and gradually increased in spacing as to the cutters of 25 the pairs between slot digging cutters, the cutters of each pair being arranged above and below the longitudinal center of the chain and being of disk-like form with peripheral cutting edges and having inclined 30 surfaces, whereby to dislodge in step by step manner those portions of a kerf between the slot formed by the first cutters and the inclined surfaces of the pairs of cutters of maximum spacing and effect such 35 dislodgment along planes substantially at right angles to the longitudinal movement of the chain.
3. A cutter chain for mining machines including a plurality of links, and a plurality
- of rotary cutters mounted thereon, certain 40 of which are in the nature of serrated disks having peripheral cutting edges curved along lines concentric with the axis of the disk and have one flat face and one smooth inclined surface opposite said flat face, said 45 cutters being mounted in vertically spaced relation in pairs of which the cutters of each pair are equi-distantly spaced upon opposite sides of the longitudinal center of the chain. 50
4. A cutter chain for mining machines including a plurality of links, and a plurality of rotary cutters mounted in connection therewith, certain of which cutters are of disk-like form and have a peripheral cutting 55 edge concentric with the axis thereof and one inclined face and one flat face, said cutters being vertically spaced in pairs with their inclined faces toward one another. 60
5. A cutter chain for mining machines having cutter supporting links, and cutters having universal connections with the opposite sides of the links whereby to rotate and incline outwardly away from one another upon engagement with the work at the active side of the cutter chain in operation. 65
6. A cutter chain for mining machines including a plurality of links, and a plurality of cutters mounted on said links, certain of which are of disk-like form and have 70 peripheral cutting edges and an inclined surface for dislodging portions of the work in use, and also have a flat surface, the said flat surface bearing against and being supported by the main body of the work when 75 the disks are in normal engagement with the work.

JOHN M. CHRISTINE.
